UNITED STATES PATENT OFFICE.

MAXIME LAMBERT, OF CHARLEROI, BELGIUM.

RAILWAY TRUCK OR WAGON.

No. 909,912.

Specification of Letters Patent. Patented Jan. 19, 1909.

Application filed May 27, 1908. Serial No. 485,279.

To all whom it may concern:

Be it known that I, MAXIME LAMBERT, citizen of France, residing at 2 Quai de Namur, Charleroi, in the Kingdom of Belgium, have invented new and useful Improvements in Railway Trucks or Wagons, of which the following is a specification.

This invention relates to improvements in railway trucks or wagons.

10 The improved truck is of considerable length and forms a platform, and is intended for the transport of articles of great length such as rails, balks, etc.

15 The essential features of the invention consist in the use of metallic cables in order to strengthen and truss the side sills of the wagon; in the method of application and of tensioning these cables on the side sills and in the articulated system of buffers of the

20 wagon.

In the annexed drawings: Figure 1 is a longitudinal elevation of the truck; Fig. 2 is a plan view; Fig. 3 is an end view; Fig. 4 is a transversal section on the line A A of Fig. 1; Fig. 5 is a transverse section made on line D D of Fig. 1; Fig. 6 shows in longitudinal section the manner of fixing the cables on the side sills; Fig. 7 is a transverse section made on the line E E of Fig. 6; Fig. 8 is a view, partly in section, showing the system of fixing the cables on the truss-posts; Fig. 9 is a transverse section made on the line F F of Fig. 8; Fig. 10 is a lateral view in elevation of the system of articulated buffers; Fig. 11 is a longitudinal section made on the axis of articulation of the bogie and on the axis of one of the buffers; Fig. 12 is a horizontal section half of which is made on the line G G of Fig. 10 and the other half on the line H H of Fig. 11; Fig. 13 is a sectional view of a detail. Fig. 14 is a detail view, on a larger scale, of the guide rail. Fig. 15 is a plan view of the same. Fig. 16 is a detail plan view of the sector for suspending the shocks and traction apparatus.

45 The wagon consists essentially of a platform P, supported by two bogies B.

The platform is designed to resist in the best possible manner the strains arising either from the load, or from the working conditions. The said platform is formed by two side sills L, connected together by cross-pieces t. Each side sill comprises a trussed beam composed of two channels l, connected by cross-bars m of cast-steel; the retaining member is formed by metallic

cables of steel n, n', of the kind which are used in mines, and by hanging-posts of cast-steel o. The cables are arranged in the longitudinal axis of the side sills; their ends pass between the two channels l and are fixed, as mentioned further on, to the upper part of the side sill. In this manner a very strong frame-work is obtained, the upper part of which forms a body which is capable of resisting the very great strains of compression, which are due to the load and to shunting and the lower part of which is formed of cable of extra hard steel, with a resistance of 120 kilogrammes per square millimeter. The use of this cable allows great lightness to be given to the whole.

The hanging-posts o, sustaining the beam, are movable at their ends; by this fact the side sills comply without any inconvenience to all movements which are due to flexibility or expansion; therefore no deformation of this beam need be feared.

Each end of the cable is inclosed in a steel-piece a, hollowed in the form of a truncated cone, in the interior of which the wires which form the cable are unraveled, bent round at their end and embedded in a mass of white metal. This piece a consists of two parts: The first a', of a square shape, is fitted into a housing provided at the upper part of a cross-bar of the side sill; the second, cut like a screw along its whole length, is capped with a screw-sleeve b, lying on a fixed point of the side sill through the medium of a washer r, applied on the cross-bar m. By this arrangement, the piece a cannot make any rotating movement, and it is sufficient to turn the screw-sleeve b on itself in order to obtain the horizontal displacement of the piece a, and in consequence, of the cable which can be regulated as desired as regards the tension. In this manner the inconveniences which the stretching of the cables would produce under the successive loads can be overcome. From one cross-frame to another the hanging posts o are connected two by two at their lower part, by means of a bar q, which maintains the distance between the hanging posts and the cables.

105 The hanging posts o supported by the cables are set according to the bi-section of the angle formed by the two bodies of these cables. In order to maintain them in this position it is necessary to arrange a stop 110 with its support on the cable without diminishing the strength of same by its mode of

anchorage. The adopted arrangement (Figs. 8 and 9) comprises two pieces; the one *c* bears a heel which stops the cross-beam; it is threaded on a certain length and ends by a trunconical portion *d*, which is divided by a saw-stroke into four thin plates forming a spring; the other is a sleeve *e* which is fitted in and screwed on the part *c*. By screwing this sleeve, the trunconical plates *d* are tightened and pressure can be brought to bear on the cable, which can be as forcible as desired.

The system of articulated buffers, which is one of the characteristic points of the invention, is arranged to remedy the inconveniences produced by vehicles of great length when traveling on curves of small radius; on these curves the ends of the vehicles tend to project outside the rails, their buffers incline, lose the contact with the neighboring vehicles and in crossing strike on the extreme cross-beams which they may break; further, the coupling hooks of two neighboring wagons become removed so much as to render the coupling impossible to make. It results from these facts, that wagons of great length cause damage to the couplings and even cause derailment, and it is generally necessary to work them singly.

In order to avoid these inconveniences this invention provides a system of articulated buffers, with their support on the platform of the wagon and transmitting to the latter the shocks received, and are capable of lateral displacement. This is done in the following manner: At each extremity of the wagon is a guide rail *f* in the form of a bow and fixed by means of supports *r* riveted in the side sills; a sector *g* of cast-steel carrying the shocks and traction apparatus, is supported by this guide rail; it slides on same by the intermediary of eight rollers *s*, and describes a circle round the axle of the pivot of the bogie *u*. This sector *g* is controlled by a fork *h* extending from the pivot of the bogie and which is guided by a retaining member *i*, fixed at the end of this bogie.

When the wagon enters a curve, the bogie, which is guided by the rail moves the fork *h* which by the intermediary of two pivots *j* moves the whole system of buffers; this latter is displaced independently from the platform of the wagon, just as if it were fixed on the bogie. On very sharp curves these buffers project somewhat laterally of the side sills of the platform. Bearing plates *k* of cast-steel are strongly fixed on the side sills and take the strain of the shock when shunting, etc.

Having now described my invention, what I claim as new and desire to secure by Letters Patent is:

1. A railway truck comprising two bogies, a platform, two side sills on which rests the

platform and each of which is formed of two channels, cross-bars connecting the channels, cross-pieces connecting the side sills, hanging posts articulated at the bottom of said side sills, and metallic cables of steel arranged in the longitudinal axes of the side sills and adapted in combination with the hanging posts to strengthen and truss said side sills, substantially as described and for the purpose set forth. 75

2. A railway truck comprising two bogies, a platform, two side sills on which rests the platform and each of which is formed of two channels, cross-bars connecting the channels, cross-pieces connecting the side sills, hanging posts articulated at the bottom of said side sills, metallic cables of steel arranged in the longitudinal axes of the side sills and adapted in combination with the hanging posts to strengthen and truss 85 said side sills, hollowed steel-pieces in which the wires at the ends of the cables are unraveled and embedded in a mass of white metal and which consists of two parts one of which is square and the other screw-threaded, a housing provided at the upper part of a cross-bar of the side sill and adapted to engage the square end of the hollow steel-piece, and a screw-sleeve screwed on the opposite end of said hollow steel-piece and adapted to regulate the tension of the cable, substantially as described and for the purpose set forth. 90

3. A railway truck comprising two bogies a platform, two side sills on which rests the platform and each of which is formed of two channels cross-bars connecting the channels, cross-pieces connecting the side sills, hanging posts articulated at the bottom of said side sills, metallic cables of steel 100 arranged in the longitudinal axes of the side sills and engaging the free ends of the hanging posts, heel pieces with spring plates surrounding the cable and bearing against the ends of the hanging posts, sleeves engaging the spring plates of the heel pieces and adapted to tighten same on the cables, hollowed steel pieces in which the wires at the ends of the cables are unraveled and embedded in a mass of white metal and which 115 is composed of two parts one of which is square and the other screw-threaded, a housing provided at the upper part of a cross-bar of the frame plate and adapted to engage the square end of the hollow steel-piece, and a screw-sleeve screwed on the opposite end of said hollow steel-piece and adapted to regulate the tension of the cable, 120 substantially as described and for the purpose set forth. 110

4. A railway truck comprising two bogies, a platform, two side sills on which rests the platform and each of which is formed of two channels, a guide rail in the form of a bow fixed to the side sills, a movable sector 130

carrying the buffers and coupling hooks and adapted to slide on the guide rail by the intermediary of rollers, a fork articulated on the pivot of the bogie and adapted to control the movable sector and a retaining member fixed at the end of the bogie and adapted to guide the fork, substantially as described and for the purpose set forth.

In testimony whereof I have signed my name to this specification in the presence of 10 two subscribing witnesses.

MAXIME LAMBERT.
